UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

OXIDE TERMINAL.

Application filed October 15, 1923. Serial No. 668,500.

To all whom it may concern:

Be it known that I, ALVIN D. KEENE, a citizen of the United States, and a resident of Pittsburgh, in the county of Allegheny and State of Pennsylvania, have invented a new and useful Improvement in Oxide Terminals, of which the following is a specification.

My invention relates to electric furnaces and particularly to terminal members for electric resistance furnaces.

One object of my invention is to provide a relatively simple and easily installed terminal member for an electric furnace of the metallic resistor type.

Another object of my invention is to provide a terminal member for metallic resistor furnaces that shall be easily and quickly connected to the ends of the resistor and that shall provide a joint having a relatively low resistance.

Another object of my invention is to provide a terminal member for metallic resistor furnaces that shall require only the simplest tools to install.

In practicing my invention, I provide a terminal rod, of relatively large diameter and of a non-oxidizable material, extending through the refractory walls of a furnace structure and connected to the end of the metallic resistor member. The inner end of the rod is provided with an opening within which is placed a metallic member that changes its crystalline structure and swells or expands upon being subjected to a relatively high temperature. The end of the resistor member, of substantially non-oxidizable material, is inserted in the opening in the end of the terminal rod and is tightly gripped or wedged therein after the first operation of the furnace.

In a modified form of device embodying my invention, a tubular rod is employed instead of a solid rod. In a further modification, an intermediate metal member may be employed to connect the co-operating ends of the terminal rod and of the resistor member.

In the drawings,

Figure 1 is a view, in vertical longitudinal section, of an electrical resistor furnace embodying my invention.

Fig. 2 is a view partially in side elevation and partially in longitudinal section, of a

furnace structure, with which it is operatively associated.

Fig. 3 is a view, partially in side elevation and partially in longitudinal section, of a modified form of device embodying my invention, and

Fig. 4 is a fragmentary view, in longitudinal section, of a still further modification of a device embodying my invention.

An electric resistance furnace 11 comprises an outer casing 12 of a suitable heat-insulating refractory material and an inner lining 13 of a suitable high-temperature resisting refractory material. The inner lining 13 and the casing 12 therefor, may be built up of a plastic mass or of bricks or blocks and enclose a furnace chamber 14 of any suitable or desired contour and dimensions.

A relatively heavy resistor member 16, preformed to comprise a plurality of straight and substantially parallel-extending convolutions is located within the chamber 14 and comprises a material that is substantially non-oxidizable, such as nichrome. Any suitable or desired means of supporting the resistor 16 may be employed and the means here shown are a plurality of spaced refractory rods 17 that secure the resistor member against the co-operating wall of the furnace chamber. As the method of supporting the resistor forms no part of my invention, it is not further illustrated or described.

A terminal member for the resistor member 16 comprises a rod 18 of a suitable non-oxidizable material, such as nichrome, that extends through an opening 19 in the refractory wall of the furnace structure, a tubular insulating member 21 being provided to more effectively insulate the terminal rod 18 from the refractory lining 13 and the casing 12.

At its inner end, the rod 18 is provided with an axial opening 22 extending into the rod for a short distance and a sleeve 23 of steel or cast iron is located within the opening 22. The sleeve 23 has an inner opening of substantially the same diameter as the resistor rod 16, one end of which is located within the sleeve 23 and is initially held therein by a set screw 24. The sleeve 23 undergoes a change of crystalline structure upon being subjected to the relatively

high temperature at which a furnace of this type operates, and swells, thereby tightly wedging the non-oxidizable resistor member 16 within the equally non-oxidizable terminal rod 18. The sleeve 23 is also oxidized upon being subjected to the relatively high temperature, thereby causing a still further swelling or expansion of the sleeve, and a tight gripping or wedging of the resistor rod 16 within the opening 22. The oxidizing sleeve 23 becomes even more highly conducting than it was originally, thereby providing a joint of relatively very low resistance.

15 Any suitable or desired means for holding the rod 18 in its proper operative position relatively to the refractory wall may be employed, and I have here shown an inner nut 25 and an outer nut 26, together 20 with a washer 27 located against the outer surface of the outer casing 12. A terminal lug 28 of usual construction may be provided to which the end of a supply circuit conductor (not shown) may be sweated, and 25 extra nut 26 is provided to securely clamp the lug 28 on the rod 18.

Instead of the rod 18, I may employ a tubular member 29 illustrated in Fig. 4, 30 within the inner end of which a sleeve 23 of steel or cast iron is located substantially as hereinbefore described in connection with the rod 18. Substantially the same means for holding the tubular rod 29 may be employed, as were hereinbefore described for 35 the rod 18.

In a still further modification, I may employ a rod 18 in combination with an intermediate member 31, of substantially non-oxidizable material, such as nichrome, that 40 is provided with two axial and aligned openings 22 and 32, to receive respectively the ends of the resistor member 16 and of the rod 18, sleeves 23 and 33 of oxidizable material being interposed between the ends of 45 the resistor member 16 and of the rod 18 and the member 31.

If a plurality of relatively short resistor members 16 are to be connected in series circuit relation to each other, connectors 34 50 of the type disclosed and claimed in my co-pending application, Serial No. 649,781 filed July 6, 1923, and assigned to the Westinghouse Electric & Manufacturing Company, 55 may be employed.

The operation of the sleeve 23 is more particularly described in the above-mentioned application, to which reference may be had for further details of operation thereof and particularly those of the connectors 34.

I have illustrated terminal rods, either solid or tubular, of relatively large cross-sectional area as compared to the resistor wire, thus insuring that only a relatively small amount of heat is generated in the

terminal rod where it is located in and extends through the refractory walls, thereby insuring a minimum amount of heat loss during the actual operation of the furnace.

Various modifications and changes may be 70 made without departing from the spirit and scope of the invention, I desire, therefore, that only such limitations shall be placed thereon as are imposed by the prior art or are set forth in the appended claims. 75

I claim as my invention:

1. A terminal structure for a resistor member, comprising a terminal member, of larger cross-sectional area than said resistor member operatively engaging the same, and 80 means in said terminal member that is operative at a high temperature to swell and tightly grip the resistor member.

2. A terminal member for a resistor member, comprising an elongated metal portion 85 having an axial opening at one end thereof, and a sleeve fitting in said opening and operatively engaging the end of said resistor member, said sleeve swelling upon being subjected to a relatively high temperature and 90 wedging said resistor in said opening.

3. A terminal member for a resistor member, comprising an elongated member of larger cross-sectional area than said resistor member and interfitting therewith, and a 95 metal member, interposed between said elongated member and said resistor member, that is operative at the operating temperature of said furnace to swell and tightly wedge said resistor member in said elongated member.

4. A terminal structure for a resistor member, comprising an elongated metal terminal member interfitting with said resistor member, and a metal member operatively engaging said resistor and said terminal member, said metal member swelling upon being subjected to a relatively high temperature and 105 tightly wedging said resistor member in said elongated terminal member.

5. A terminal structure for a resistor member of non-oxidizable material, comprising a terminal member of non-oxidizable material and of larger cross-sectional area than said resistor interfitting therewith, and a 115 metal member interposed between said terminal member and said resistor member, said metal member changing its granular structure and oxidizing upon being subjected to a high temperature whereby it swells and tightly wedges said resistor in said terminal member.

6. A terminal structure for a resistor member of substantially non-oxidizable material, comprising an elongated terminal member, of substantially non-oxidizable metal, having an opening therein for receiving one end of said resistor member, and a metal member operatively engaging said terminal member and said resistor member and ef 125 130

fective to change its granular structure and oxidize upon being subjected to a high temperature whereby it swells and wedges said resistor member in said terminal member.

- 5 7: A terminal structure for a resistor member, located in a casing, comprising an elongated terminal member, of substantially non-oxidizable metal extending through a wall of the casing and having an opening in
10 its inner end for interfitting with one end of the resistor member, means for maintaining

it in position in the wall, and a metal member inside of said terminal and operatively engaging said resistor and swelling upon the application of heat thereto whereby it ¹⁵ wedges the end of the resistor member in said terminal member.

In testimony whereof I have hereunto subscribed my name this 9th day of October, 1923.

ALVIN D. KEENE.
